United States Patent

Des. 237,486
Patented Nov. 4, 1975

237,486

STAIR RAILING

Paul C. Wutzke, 9312 Mazatlan Way,
Elk Grove, Calif. 95624

Filed Apr. 18, 1973, Ser. No. 352,251

Term of patent 14 years

Int. Cl. D25—02

U.S. Cl. D13—7 R

FIG. 1 is an isometric view of a stair railing, showing my new design, the opposite side being in mirror symmetry;

FIG. 2 is a front elevational view;

FIG. 3 is a top plan view of FIG. 4;

FIG. 4 is a side elevational view, the opposite side being in mirror symmetry; and,

FIG. 5 is a rear elevational view.

I claim:

The ornamental design for a stair railing, as shown and described.
